UNITED STATES PATENT OFFICE.

ANDREW L. HATFIELD, OF NEWARK, NEW JERSEY.

MACHINE FOR SHARPENING SAFETY-RAZOR BLADES.

1,123,871.

Specification of Letters Patent.

Patented Jan. 5, 1915.

Application filed November 13, 1911. Serial No. 659,884.

To all whom it may concern:

Be it known that I, ANDREW L. HATFIELD, a citizen of the United States, residing at Newark, Essex county, New Jersey, have invented certain new and useful Improvements in Machines for Sharpening Safety-Razor Blades, &c., of which the following is a specification.

The objects of the invention are to provide a novel and highly efficient machine for sharpening thin blades of that general character which are commonly employed in connection with safety razors, the said machine being automatic in its action and being adapted to be driven by power; to provide novel means for manipulating the blades and grinding elements so as to quickly and uniformly sharpen the blade; to give the grinding elements a longitudinal movement as well as rotary and thus cause them to wear evenly; to provide a construction which admits of the blades being quickly placed in operative position or removed therefrom; to enable either a single blade or a plurality of blades to be removed or inserted at once; to conveniently and thoroughly magnetize the blades as they are sharpened, and to obtain other advantages and results as may be brought out in the following description.

Referring to the accompanying drawings, in which like numerals of reference indicate the same parts throughout the several figures, Figure 1 is a side elevation of a machine for sharpening safety razor blades constructed in accordance with the invention; Fig. 2 is an end view of the same; Fig. 3 is a vertical transverse sectional view on the line A—A of Fig. 1; Fig. 4 is a longitudinal sectional view through the upper set of grinding rolls; Fig. 5 is a top plan view of one of the blade holders and a portion of the plate for supporting the blade holders; Fig. 6 is an enlarged top plan view of one of the blade holders detached; Fig. 7 is a side elevation of one of the blade holders, one end thereof being removed; Fig. 8 is an enlarged transverse sectional view through one of the blade holders on the line B—B of Fig. 7; Fig. 9 is an enlarged detail view of one of the fastening pins for retaining the blade holders in position; Fig. 10 is an enlarged sectional view on the line C—C of Fig. 5, the blade holder being removed; Fig. 11 is a front view of the portion of the blade

carrying plate shown by Fig. 10; Fig. 12 is a transverse sectional view through the rocking carriers and the connecting members between the same, the said section being taken on the line D—D of Fig. 1; Fig. 13 is an enlarged detail view of the cam mechanism for rocking the carriers, the said section being taken on the line E—E of Fig. 1, and Fig. 14 is a detail view of the link between the bell crank lever and the arm of the carrier.

Specifically describing the present embodiment of the invention, the numerals 1 designate a pair of spaced standards which constitute the supporting frame upon which the grinding and sharpening mechanism is mounted. The lower ends of the standards 1 are provided with the feet 2 which may be secured to any suitable base, while the upper ends of the standards are connected by a cross bar 3. An upper set of rolls 4 and 5, and also a lower set of rolls 6 and 7 are mounted between the standards 1, the rolls of each set having a spaced and parallel relation and revolving in opposite directions. Each of the rolls is formed with trunnions 8, the various trunnions passing loosely through bearing sleeves 9 in the standards 1 and the length of the rolls being slightly less than the distance between the standards so that the rolls can have a longitudinal as well as a rotary movement. This longitudinal movement is in many cases very important, since it prevents nicks or the like in the blades from wearing annular ridges in the rolls so as to decrease the efficiency thereof.

The top roll 4 of the upper pair of rolls is provided upon one side of the machine with a pulley 10 which is connected by a belt 11 to a similar pulley 12 rigid with the top roll 6 of the lower set of rolls. The roll 6 is also provided with a second pulley 13 engaging a belt 14 which also passes around a pulley 15 upon a drive shaft 16 which may receive power from any suitable source, and is preferably located under the grinding and sharpening device, as indicated by Fig. 2. On the opposite side of the machine, the lower roll 5 of the upper set of rolls is provided with a pulley 17 which is connected by a belt 18 to a similar pulley 19 upon the lower roll 7 of the lower set of rolls. This lower roll 7 is also provided with a pulley 20 which is connected by a belt 21 to a pulley upon the drive shaft 16, the said belt 21

being crossed, as indicated by Fig. 2, so that the upper roll and lower roll of each set will revolve in opposite directions.

A cam shaft 22 is journaled upon the standards 1 near the lower ends thereof, the said cam shaft receiving power in some suitable manner as by means of the belt and pulley connection 23 with a countershaft 24 which is shown as having a belt and pulley connection 25 with the main drive shaft 16. The cam shaft 22 projects beyond one end of the machine where it is provided with a disk 26 having a cam groove 27 therein. This cam shaft is also provided with a disk 28 having a cam groove therein, the said cam groove including offset straight portions 29 which are connected at diametrically opposite points by sharply inclined portions 30. A member operating within the groove will thus be quickly shifted back and forth between the straight portions 29 of the groove as the cam shaft is rotated. A roll shifting lever 31 is pivoted at an intermediate point in its length as indicated at 32 upon a bracket 33 projecting from one of the standards 1. The lower end of this lever is provided with a projection 34 which is received within the cam groove 27 of the disk 26, while the upper end of the lever is notched at 35 and loosely receives a pin 36 upon a bar 37 connecting the trunnions of the various rolls. This bar is provided with bearing sleeves 38 which receive the trunnions and are fitted between collars 39 thereon so that the rolls will be moved longitudinally as the bar is forced toward and away from the standard 1. As the cam shaft 22 is rotated the lever 31 is reciprocated back and forth so as to move the various rolls longitudinally and cause them to operate uniformly upon the razor blades. As above mentioned this longitudinal movement of the rolls also has the advantage of preventing any nicks in the blades from wearing grooves or ridges upon the rolls and decreasing the efficiency thereof.

A rocking blade carrier 40 is provided for each pair of the rolls, the said blade carriers being shown in the present instance as provided at opposite ends thereof with pendent ears 41 which are loosely mounted upon transverse rods or shafts 42 connecting the standards. A blade carrying plate 43 is detachably mounted upon each of the rocking carriers 40, the said plates being shown as provided at opposite ends thereof with slots 44 receiving screws 45 which project from the carriers and are engaged by clamping nuts 46. These blade carrying plates are each provided at suitable intervals with upwardly projecting lugs or ears 47 which are arranged in pairs and are provided with rearwardly opening bearing notches 48. Each pair of the lugs 47 is designed to receive a blade holder 49, the

said blade holders being formed with oppositely projecting trunnions 50 which are removably received within the bearing notches 48. A spring strip 52 is arranged under each of the blade holders, the intermediate portion of the spring strip being secured to the plate 43 in some suitable manner as by means of a screw 53, while the ends of the spring are deflected upwardly so as to engage the blade holder 49 on opposite sides of the pivot point thereof. The forward end of the spring enters a notch 51 in the under side of the holder, see Fig. 7 more particularly, and thus releasably retains the holder in place for operation of the rolls upon the blade carried by it. The ends of the spring are engaged by screws 54 passing upwardly through forwardly and rearwardly projecting wings 55 upon the plate 43, and by manipulating these screws the tension in the springs can be adjusted as may be desired. The blade holders are thus held yieldingly in position, so that as they are rocked back and forth the blades will be alternately held yieldingly against the two rolls.

If desired, arched pins 86 may be provided for the purpose of retaining the blade holders in position, the arms of the arched pins fitting within openings in the lugs 47 so as to extend across the notches 48 and retain the trunnions 50 therein.

Each blade holder 49 is provided with a head 56 having jaws 57 which are adapted to grip a thin blade so as to retain the same securely in position. These jaws are shown as connected by the clamping screws 58 which may be loosened for removing a blade or placing a blade in position, and tightened to grip a blade preparatory to applying the holder to the machine for the purpose of sharpening the blade. It will be observed that the head 56 is formed with a rearwardly projecting axial stem 59 which is loosely received within a corresponding socket in the end of the holder 49 and is provided with a transverse opening receiving a pin 60. As indicated more clearly by Fig. 8, this transverse opening is flared at the opposite ends thereof to admit of the head having a slight rotary movement independent of the blade holder. This enables the blade to readily accommodate itself to the rolls so that the rolls always act upon the blade in a uniform manner.

The upper and lower blade carriers 40 are provided with arms 61 which are connected by a link 62 for causing the two blade carriers to rock together. The lower blade carrier 40, as indicated more clearly in Fig. 13, is provided with a second lateral arm 63 which has an operative connection with one arm of a bell crank lever 64, the opposite arm of the said bell crank lever being provided with a projection 65 which travels in

the cam groove of the disk 28. A link 66 is provided for connecting the bell crank lever to the arm 63. This link, as will be seen more clearly in Figs. 13 and 14 is 5 formed at opposite ends thereof with the sleeves 67, one of the said sleeves receiving a stem 68 projecting from a block 69 which is connected to the arm 63 by a screw 70, while the opposite sleeve 67 receives a similar 10 stem 71 projecting from a block 72 which is secured to the upper arm of the bell crank lever 64 by a screw 73.

With the above construction it will be obvious that as the cam shaft 22 is rotated 15 during the operation of the machine the bell crank lever 64 will be moved back and forth so as to simultaneously rock the blade carriers 40. The various blades in the different holders 49 are thereby brought successively 20 into engagement with the upper and lower rolls, the swivel connection between the heads 56 and the holders enabling the blades to adjust themselves to the rolls, while the springs 52 hold the blades yieldingly in engagement 25 with the rolls. When the projection 65 is in engagement with one of the straight portions 29 of the cam groove in the disk 28 the blades are in engagement with one of the rolls, while when the said projection 65 is in engagement with the opposite straight portion of the cam groove the blades are in engagement with the opposite roll. The inclined portions 30 of the cam grooves serve to shift the blades quickly 35 from engagement with one of the rolls to engagement with the opposite roll. It will accordingly be obvious that the blades are in engagement with one or the other of the rolls practically all the time, the shifting 40 from one roll to the opposite roll being very quickly accomplished.

It has been found that razor blades and the like retain an edge for a much longer period of time if they are magnetized. 45 Means has accordingly been provided for subjecting the blades to the action of a magnetic field and magnetizing the same as they are sharpened. The upper rolls 4 and 5 have a hollow formation and have oppositely wound electro magnets 74 and 75 arranged transversely therein, the pole pieces 76 at the ends of the magnets being secured to the metallic shells of the rolls in some suitable manner as by means of the screws 50 77. Plugs 78 of wood or some similar material are inserted in the ends of the rolls to carry the trunnions, and these plugs are provided with passages for the wires leading to the magnets. It will also be observed that the ends of the plugs have conductor plates 79 applied thereto and that the lead wires 80 of the magnets are connected to the said plates at opposite ends of the rolls. At one end of the machine a 55 double brush 81 is secured to the standard 1 and insulated therefrom; the opposite ends of the brush frictionally engaging the conductor plates at the adjacent ends of the rolls. At the other end of the machine the plate 79 of the upper roll 4 is engaged by 70 a brush 82 connected to a binding post 83, while the plate 79 of the lower roll 5 is engaged by a brush 84 connected to a binding post 85. The terminals of an electric circuit are designed to be secured to the binding posts 83 and 85, and the current will then pass continuously through the magnets as the rolls rotate so as to produce a magnetic field around the blades and magnetize the same as they are sharpened. The 75 brushes would, of course, possess the necessary resiliency to permit the rolls to be shifted longitudinally as has been previously mentioned.

In operation, the blades to be sharpened 80 are ground first upon the lower set of rolls 6, 7, and are finished upon the upper set of rolls 4, 5, which are of the different character required for honing or finishing. This means that each blade in its holder is inserted first at the lower set of rolls and then removed and inserted again for the upper set of rolls. By my improved construction, either one holder and its blade can be thus shifted and manipulated or a plurality of 90 holders can be handled at the same time. This is effected by means of the plates 43, upon each of which I have shown mountings for six individual blade holders, although the number might of course be varied as desired. By removing this plate 43 from the lower carrier 40 and placing it upon the upper carrier 40, six blades can be handled at once. Or, if desired, any individual holder can be removed from a plate 43 upon 95 the lower carrier 40 and inserted upon the plate of the upper carrier. Great convenience and facility in the work of sharpening is thus secured.

It will be noted that the cams 26 and 28 are so arranged and timed that while the blades are resting upon one roll of a set the rolls are shifted longitudinally for their entire range of movement and back again to the starting point. The cam 28 and connections then throw the blades into connection with the other roll of the set, and the rolls shift again as before. This is continued indefinitely.

Having thus described the invention, 110 what I claim is:

1. The combination with a sharpening element having a sharpening surface with diametrically opposite portions, of a magnet having opposite ends or poles adjacent 115 to said diametrically opposite portions of the sharpening surface respectively.

2. A blade sharpening machine including 120 a sharpening roll, means for rotating said roll, means for holding a blade in engage- 130

- ment with the sharpening roll, and a magnet arranged transversely within the roll with its ends or poles adjacent separated parts of the peripheral surface of the roll.
5. 3. A blade sharpening machine including a pair of sharpening rolls, means for rotating said rolls, means for holding a blade alternately in engagement with the two rolls, oppositely wound electromagnets arranged one transversely within each roll with its ends or poles adjacent separated parts of the peripheral surface of the roll, and means for conveying current to the two electromagnets as the rolls revolve so as to magnetize the blades as they are sharpened.
10. 4. A blade sharpening machine including a pair of sharpening rolls, a rocking member provided with a pair of lugs having bearing notches therein, a blade holder having trunnions adapted to be received within the bearing notches, a spring strip carried by the rocking member and engaging the blade holder to retain the blade in a yielding engagement with the roll, and means for adjusting the tension of the spring.
15. 5. A blade sharpening machine including a pair of sharpening rolls, a rocking member provided with a pair of lugs having bearing notches therein, a blade holder having trunnions adapted to be received within the bearing notches, a spring strip carried by the rocking member and having opposite ends thereof in engagement with the blade holder, and screws engaging the ends of the spring strip to regulate the tension therein.
20. 6. A blade sharpening machine including a sharpening roll mounted to have both a rotary and a longitudinal movement, means for retaining a blade in engagement with the sharpening roll, a drive shaft having an operative connection with the sharpening roll, a member provided with a cam groove, a shifting lever pivoted between its ends and provided at one end with means for engaging the cam groove, and a bar engaging the opposite end of the lever and having an operative connection with the roll so as to move the roll longitudinally as it is rotated.
25. 7. A blade sharpening machine including a plurality of sharpening rolls mounted to have both a rotary and a longitudinal movement, means for retaining a blade adapted to alternately apply said blade to two adjacent rolls, means for shifting the rolls longitudinally back and forth, and means for applying the blade to one roll during movement thereof in one direction and to the other roll during movement thereof in the opposite direction and changing the application of the blade from one roll to the other in synchronism with the change of direction of longitudinal movement of the rolls.
30. 8. A blade sharpening machine including a plurality of sharpening rolls mounted to have both a rotary and a longitudinal movement, means for retaining a blade, means for shifting said rolls longitudinally back and forth simultaneously, and means for applying said blade alternately to said rolls the change of application of the blade from one roll to the other being synchronized with the change in direction of longitudinal movement of the rolls.
35. 9. A blade sharpening machine including a pair of sharpening rolls mounted to have both a rotary and a longitudinal movement, a rocking blade carrier, a blade holder upon the blade carrier, the blade being brought alternately into engagement with the two rolls as the carrier is rocked, means for driving the rolls, a pair of disks provided with cam grooves, means for driving the disks, a shifting lever pivoted between its ends and engaging the groove of one of the disks, an operative connection between the said lever and the rolls for moving the rolls longitudinally, a second lever provided with means for engaging the groove of the opposite disk, and an operative connection between the second lever and the blade carrier for rocking the same.
40. 10. In a blade sharpening machine, a sharpening roll, a blade holder provided with trunnions and having a rearwardly facing stop, a support having rearwardly open bearings adapted to receive said trunnions, and a leaf spring carried by said support between said bearings and adapted to engage said blade holder to press the blade into yielding engagement with the roll and adapted at one end to engage said stop.
